UNITED STATES PATENT OFFICE.

CHARLES THOMAS MASON, OF SUMTER, SOUTH CAROLINA, ASSIGNOR TO SPLITDORF ELECTRICAL COMPANY, OF NEWARK, NEW JERSEY, A CORPORATION OF NEW JERSEY.

ELECTRIC GENERATOR.

1,236,732.

Specification of Letters Patent. Patented Aug. 14, 1917.

Application filed September 15, 1916. Serial No. 120,325.

To all whom it may concern:

Be it known that I, CHARLES THOMAS MASON, a citizen of the United States, residing at Sumter, in the county of Sumter 5 and State of South Carolina, have invented certain new and useful Improvements in Electric Generators, of which the following is a specification, reference being had to the accompanying drawing.

10 The invention relates to new and useful improvements in electric generators and particularly to that class of generators used for igniting the charge in an internal combustion engine, which generators are generally termed magnetos.

An object of the invention is to provide a magneto of the above character having a primary field generating flux, a secondary field structure carrying windings and means 20 for shifting the flux from the primary field to the secondary field structure with automatic means for advancing and retarding said flux shifting means depending upon the speed of rotation thereof.

25 A further object of the invention is to provide a magneto of the above character with manually operated means for controlling said automatic means.

A still further object of the invention is 30 to provide a magneto having a permanent magnet, a rotor, a current generating coil and a core therefor in inductive relation to the rotor with means whereby the rotor may be automatically adjusted angularly relative to its supporting and operating shaft for timing purposes according to the speed of said shaft.

A still further object of the invention is 35 to provide a magneto of the above character wherein the cam for actuating the interrupter is carried by the rotor, so that the cam and rotor may be simultaneously and automatically adjusted for timing purposes.

A still further object of the invention is 40 to provide a device of the above character with manually operated means for controlling said automatic means.

These and other objects will in part be 45 obvious and will in part be hereinafter more 50 fully disclosed.

In the drawings, which show by way of

illustration, one embodiment of the invention:

Figure 1 is a sectional view through a magneto having my improvements applied thereto;

Fig. 2 is a view more or less diagrammatically of the current generating coil, the windings thereof, the interrupter associated with said coil and the means for operating 60 said interrupter from the rotor;

Fig. 3 is a plan view of the operating shaft for the rotor; and

Fig. 4 is a plan view of the rotor shaft;

Fig. 5 is a plan view of the rotor showing 65 the cam slots for angularly shifting the same.

The invention is directed particularly to a magneto for ignition purposes wherein a current generating coil is provided with a 70 core in inductive relation to a rotor coöperating with a permanent magnet and furnishing the flux of said magnet to said core. Associated with the core is an interrupter operating to break the primary circuit at 75 the time of ignition.

The rotor is mounted on an operating shaft and carries a cam for actuating the interrupter. This rotor is capable of being shifted angularly on its operating shaft and 80 when so shifted the timing of the spark in the engine cylinder is either retarded or advanced depending on the direction of shift of the rotor relative to its operating shaft. This shifting of the rotor brings about a 85 simultaneous adjustment of the position of the rotor relative to the core of the current generating coil and the interrupter operating cam so that the rotor will be in position for maximum spark when said spark is advanced or retarded.

The rotor is shifted on its supporting shaft automatically by a governor which responds to the speed of the shaft and this provides automatic means for advancing and 95 retarding the flux shifting means which depends upon the rotative speed thereof. In addition to the automatic means for shifting the position of the rotor there is also a manually operated means for controlling said 100 automatic means.

Referring more in detail to the drawings,

my improved magneto consists of a permanent magnet 1 having oppositely disposed and parallel pole faces. Each pole face is provided with an opening 2 in which is 5 mounted a supporting frame 3 having bearings for the shaft 4 which extends through the pole faces. This shaft 4 carries a rotor 5. The rotor 5 is formed with the usual 10 rotor wings and the spaces in and about the wings are filled with brass, the whole member being cylindrical. This rotor operates between the pole pieces 6 and 7 of a core 8 which is made in the usual way and on this core 8 is mounted a generating coil 9.

15 The generating coil consists of a primary winding 10 and a secondary winding 11. One terminal of the primary winding 10 leads to a contact 12, while the other terminal is connected to the secondary winding. 20 The secondary winding is connected to the ignition terminals, indicated at 13 in Fig. 2 of the drawings. One of these terminals is grounded. Coöperating with the contact 12 is a movable contact 14 carried by a lever 15. The rotor 4 is provided 25 with cams 16 and 17 which engage the lever 15, and these cams operate to separate the contacts 12 and 14 at the proper time for producing the spark at the spark terminals 18.

The shaft 4 is provided with a recess 18 and also with cam slots 19 and 19^a. The 30 rotor assembly is provided with cam slots 20 and 20^a. Located within the recess 18 is a rod 21 which is provided with an opening 22 and a pin 23 extends through this opening in the rod 21 and through the slots 19, 35 19^a, 20 and 20^a. These slots are so formed that a movement of the rod 21 endwise in one direction will shift the rotor assembly 40 angularly in one direction relative to the supporting shaft therefor, while a movement of the rod in the other direction will shift the rotor assembly in the opposite direction. It will readily be seen that when 45 the rotor assembly is shifted, the interrupter cam is also shifted. This interrupter cam is so shaped as to actuate the interrupter in the proper time in the rotation of the rotor 50 relative to the core 8 as to produce a maximum spark. After these parts have once been properly adjusted, it will be apparent that all adjustments for either an advanced or a retarded spark will give a maximum 55 spark.

The rod 21 is moved endwise as herein shown by an automatic governor which is influenced by the speed of the operating shaft 4. This governor is of a well known 60 type and consists of four springs 22 each of which is provided with a weight 23. The springs are connected at their inner ends as at 24 to the shaft 4 while the outer ends of these springs are connected at 25 to the end

of the rod 21 which is slightly enlarged. 65 The rod 21 is bored out at 26 to receive a small piston 27 which is connected to a rod 28. The rod 28 is connected to a hand lever 29. Located directly in rear of the piston is a spring 30. This spring is confined 70 between the piston at 27 and an end cap 31 on the end of the rod 21.

It will be understood, of course, that the magneto shaft 4 is geared to the engine shaft and, therefore, this shaft 4 will be 75 operated in timing with the engine shaft, increasing its speed or decreasing its speed in accordance with the variation in the speed of the engine. When the speed of the engine increases the weights 23 through the 80 action of centrifugal force thereon will move out, thus expanding the governor and this outward movement of the weights bending the springs 22 will push the rod 21 farther into the shaft 4, causing the rotor assembly 85 5 to change its angular relation to the supporting shaft and also to the engine shaft, thus advancing the spark in accordance with the speed of the engine. As the engine slows down the retarded movement 90 will take place and the pressure of the governor springs against the rod 21 will be less causing it to withdraw from the recess in the shaft 4 and thus turning the rotor 95 angularly in the opposite direction and retarding the spark.

The hand controlled lever is used when the engine operates under a suddenly applied heavy load while the rotation of the engine shaft is relatively high. The governor will cause the spark to advance and the engine may "knock." By the use of the hand lever or throttle control 29 the spring 30 may be compressed to counteract the lateral force of the governor 5 or if desired 100 sufficient force may be applied to the member 10 to slide the rod 21 so as to retard the spark. When it is desired to allow the governor to control the spark in automatically advancing or retarding the same, the 105 piston 27 is moved toward the right hand end of the recess 26, as viewed in Fig. 1 of the drawings.

From the above description, it will be apparent that I have provided an ignition 110 magneto having a primary field generating flux and a secondary field structure which carries windings and which receives the flux from said primary field. Means is also provided for intermittently completing and reversing the path of flux from the primary field to the secondary field structure, which as shown in the drawings, is in the form of the rotor movable about an axis at right angles to the face of the magnet furnishing 115 the flux. I have also provided automatic means for advancing and retarding said flux shifting means which automatic means de- 120 125

pends upon the rotative speed of the operating shaft of the magneto or the operating shaft of the engine.

I have also provided manually operated means in the lever 29 whereby this automatic means may be controlled and the same rendered ineffective when desired.

It is obvious that minor changes in the details of construction and the arrangement 10 of parts may be made, without departing from the spirit of the invention, as set forth in the appended claims.

Having thus described my invention, what I claim as new and desire to secure by Letters 15 Patent, is:—

1. An ignition magneto including in combination a primary field generating flux, a secondary field structure adapted to receive flux from said primary field, a current generating coil associated with said secondary field structure, means for shifting the flux from the primary field to the secondary field including a driving shaft in the magneto, automatic means for advancing and 25 retarding said flux shifting means in relation to said shaft depending upon the rotative speed thereof and manually operated means for controlling said automatic means.

2. An ignition dynamo including in combination a flux creating element, a flux receiving element, a current generating coil carried by said flux receiving element, an interrupter associated with said coil, an interrupter operating device, means including 35 a driving shaft in the magneto for shifting the flux from the flux creating element to the flux receiving element and automatic means for simultaneously adjusting the interrupter operating device and the flux shifting means in relation to said shaft in accordance with the speed of the magneto for timing purposes.

3. An ignition magneto including in combination a permanent magnet, a flux receiving core, a coil carried by said core, an interrupter associated with said coil, an interrupter operating device, a rotor for furnishing flux to the core and automatic means for simultaneously adjusting the interrupter 50 operating device and the rotor in accordance with the speed of the magneto for timing purposes.

4. An ignition magneto including in combination a permanent magnet, a flux receiving core, a coil carried by said core, an interrupter associated with said coil, an interrupter operating device, a rotor for furnishing flux to the core and automatic means for simultaneously adjusting the interrupter 55 operating device and the rotor in accordance with the speed of the magneto for timing purposes, and manually operated means for controlling said automatic means.

5. An ignition magneto including in com-

bination a permanent magnet, a core, a current generating coil carried by the core, a rotor for furnishing the flux to said core, a shaft in the magneto supporting said rotor and automatic means for shifting said rotor angularly about said shaft in accordance 70 with the speed of the shaft for timing purposes.

6. An ignition magneto including in combination a permanent magnet, a core, a current generating coil carried by the core, a 75 rotor for furnishing the flux to said core, a shaft in the magneto supporting said rotor and automatic means for shifting said rotor angularly about said shaft, in accordance 80 with the speed of the shaft for timing purposes and manually operated means for controlling said automatic means.

7. An ignition magneto including in combination a permanent magnet having spaced parallel pole faces provided with openings 85 extending therethrough, a shaft extending through said openings, a rotor mounted on said shaft, a normally stationary current generating coil, a core therefor in inductive relation to the rotor and automatic means 90 for angularly adjusting said rotor on said shaft in accordance with the speed of the shaft for timing purposes.

8. An ignition magneto including in combination a permanent magnet having spaced 95 parallel pole faces provided with openings extending therethrough, a shaft extending through said openings, a rotor mounted on said shaft, a normally stationary current generating coil, a core therefor in inductive 100 relation to the rotor and automatic means for angularly adjusting said rotor on said shaft in accordance with the speed of the shaft for timing purposes, said last named means including a rod movable endwise on 105 the shaft, a governor connecting the shaft and the rod and devices operated by the endwise movement of the rod for shifting the rotor.

9. An ignition magneto including in combination a permanent magnet having spaced parallel pole faces provided with openings extending therethrough, a shaft extending through said openings, a rotor mounted on said shaft, a normally stationary current 115 generating coil, a core therefor in inductive relation to the rotor and automatic means for angularly adjusting said rotor on said shaft in accordance with the speed of the shaft for timing purposes, said last named 120 means including a rod movable endwise on the shaft, a governor connecting the shaft and the rod and devices operated by the endwise movement of the rod for shifting the rotor and manually controlled means for 125 preventing the endwise movement of said rod through the influence of said governor.

10. An ignition magneto including in

- combination a permanent magnet having spaced parallel pole faces provided with openings extending therethrough, a shaft extending through said openings, a rotor 5 mounted on said shaft, a normally stationary current generating coil, a core therefor in inductive relation to the rotor and automatic means for angularly adjusting said rotor on said shaft in accordance with the 10 speed of the shaft for timing purposes, said last named means including a rod movable endwise in a recess formed in the shaft of said rotor, a pin carried by the rod, a cam slot formed in the rotor whereby when said 15 rod is moved endwise said rotor is angularly shifted on said shaft, a governor connecting said rod and said shaft and operated by centrifugal force for moving the rod endwise in accordance with the speed of the shaft.
- 20 11. An ignition magneto including in combination a permanent magnet having spaced parallel pole faces provided with openings therethrough, a shaft extending through said openings, a rotor mounted on said shaft, 25 a normally stationary current generating coil, a core therefor in inductive relation to the rotor and automatic means for angularly adjusting said rotor on said shaft in accordance with the speed of the shaft for timing purposes, said last named means including a rod movable endwise in a recess formed in the shaft of said rotor, a pin carried by the rod, a cam slot formed in the rotor whereby when said rod is moved endwise said rotor is angularly shifted on said shaft, a governor connecting said rod and said shaft and operated by centrifugal force for moving the rod endwise in accordance with the speed of the shaft.
12. An ignition magneto including in combination a permanent magnet, a rotor, an operating shaft for said rotor extending at right angles to the pole faces of said magnet, a current generating coil, a core therefor in inductive relation to said rotor, automatic means depending upon the speed of said shaft for shifting the angular position of the rotor on the shaft and manually operated means for preventing said automatic means from shifting the rotor.

In testimony whereof I hereunto affix my signature.

CHARLES THOMAS MASON.
